The ornamental design for an outdoor garden string lamp, as shown and described.

DESCRIPTION

FIG. 1 is a top perspective of an outdoor garden string lamp showing my new design;

FIG. 2 is a front view thereof, a rear view being a mirror image of the front view;

FIG. 3 is a left side view thereof, a right side view being a mirror image of the left side view;

FIG. 4 is a top view thereof;

FIG. 5 is a bottom view thereof;

FIG. 6 is a partially enlarged view indicating the circled area “6” in FIG. 1; and,

FIG. 7 is a bottom perspective view thereof.

The broken lines indicating an enlargement portion of the design form no part of the claimed design.
